UNITED STATES PATENT OFFICE.

MOSES CHERRY, JR., OF LARCHMONT MANOR, NEW YORK.

WARDROBE TRUNK.

1,078,715.

Specification of Letters Patent. Patented Nov. 18, 1913.

Application filed March 13, 1913. Serial No. 753,992.

To all whom it may concern:

Be it known that I, MOSES CHERRY, Jr., a citizen of the United States, and a resident of Larchmont Manor, in the county of 5 Westchester and State of New York, have invented a new and Improved Wardrobe-Trunk, of which the following is a full, clear, and exact description.

This invention relates to wardrobe trunks, 10 and has reference more particularly to a carriage frame forming the support for the clothes hangers.

The object of the invention is to provide a simple, strong and compact carriage, 15 which will accommodate hangers, extending through the entire width of the trunk and will prevent any displacement of the hangers when engaged in the said carriage frame.

The invention consists of the construction 20 and combination of parts to be more fully described hereinafter and fully set forth in the claims.

Reference is to be had to the accompanying drawings forming a part of this specification, in which like characters indicate 25 corresponding parts in all the views and in which:

Figure 1 is a perspective view of a portion of a wardrobe trunk partly broken out 30 showing an embodiment of my invention; and Fig. 2 is an enlarged section of one end of the trunk showing the structure of the guide and carriage frame.

Referring to the drawings, 5 represents 35 a trunk of well known form to the top and sides of which are secured brackets 6 properly bent and provided with an additional support 7 riveted thereto or secured in any suitable way. Secured to said brackets are 40 U-shaped guides 8. The U-shaped guides, secured to both longitudinal sides of the trunk near the top thereof, extend through nearly the entire depth of the trunk body proper, as can be seen from Fig. 1. The 45 upper portion of the U-shaped guide 8 is slightly shorter and raised, forming a lip 9.

Reciprocating in the U-shaped guides 8 is a carriage frame 10 formed of two L-shaped members 11 engaging the U-shaped 50 member 8, and two members 12 binding the extremities of the said L-shaped members. The rear member 12 is provided with a chain, or any other similar element connecting it to the back of the trunk (not shown in the drawing), whereby the carriage frame 10 cannot pull entirely out of the U-

shaped guides 8 but only to such length that the rear portion of the carriage remains always engaged between the upper and lower front portions of the U-shaped guides. 80

The L-shaped member 11 slides in the U-shaped guide 8 with its longer side engaged between the upper and lower portions of the U-shaped member and having its projecting edge portion 13 from its base 65 extending slightly out of the U-shaped guide 8. A garment hanger 14 is provided with grooves 15 near its end, and with said grooves it engages the projecting edge portion 13 of the L-shaped member, the upper 70 side of the garment hanger 14 engaging the upper side of the U-shaped guide 8 so that the garment hanger can slip on the L-shaped member but cannot be displaced vertically with reference to Fig. 1, as it is prevented 75 by the upper side of the U-shaped guide 8.

The number of hangers 14 that can be provided on the L-shaped member varies according to the desire of the person using the trunk. It can be easily seen that when 80 the garment hangers 14 resting on the L-shaped member 11 are forced into the trunk, when the carriage 10 is moved in the lip 9 of the U-shaped guide 8 will allow an easy entrance to same. Furthermore, the garment hanger 14, which carries the clothes, 85 can then be removed through the upper portion of the carriage 10, when same is pulled out of the trunk, as shown in Fig. 1, without any trouble, the clothes passing between the L-shaped members 11. This structure allows the use of clothes hangers substantially as wide as the distance between the L-shaped members 11; and the same can always be removed by a direct pull through the carriage 90 frame, or, if desired, the garment hanger 14 may be raised slightly so as to disengage the grooves 15 from the projecting edge portion 13 of the L-shaped member and then one end of the garment hanger 14 made to 100 pass under the L-shaped member, which will make the other end enter into the space between the L-shaped members, allowing the passage of the garment hanger 14 through the lower portion of the carriage frame. 105

It can be easily seen that the grooves 15 of the garment hanger 14 engaging the projecting edge portion 13 of the L-shaped member are prevented from wobbling on the L-shaped members. This allows a far easier compressing and gives more assurance of the clothes remaining undisturbed during 110

the journey than with a complicated device which reduces the space between the guiding members, and consequently prevents the utilization of the entire space for clothing.

5 Having thus described my invention, what I claim and desire to secure by Letters Patent is:

10 1. In a wardrobe trunk, a combination of U-shaped guide members secured to the trunk and having an upper front end turned up, with a clothes support carriage frame comprising L-shaped members adapted to reciprocate in said guides; and hangers normally engaging with their extremities said 15 L-shaped members and the upper side of said U guides.

20 2. In a wardrobe trunk, a combination of U-shaped guide members secured to the trunk and having an upper front end turned up, with a clothes support frame comprising L-shaped members adapted to reciprocate in said guides and having a longitudinal projecting portion on the horizontal side and a clothes hanger having grooves engaging said

projections on said L member and normally 25 engaging with its ends between said U guides and said L members.

3. In a wardrobe trunk, a combination of U-shaped guide members secured to the trunk and having an upper front end turned 30 up, with a clothes support frame comprising L-shaped members adapted to reciprocate in said guides and having a longitudinal projecting portion on the horizontal side projecting outside of said U-shaped guides; and 35 a clothes hanger having grooves near the ends thereof engaging said projections of said L members and normally having the upper and lower surfaces of its ends engaged by said L-shaped members and said U-shaped members.

In testimony whereof I have signed my name to this specification in the presence of two subscribing witnesses.

MOSES CHERRY, JR.
